DESIGN FOR A DRAFTING MACHINE ELBOW

Lawrence E. Blazey, Cleveland, Ohio, assignor to
Keuffel & Esser Company, Hoboken, N. J., a
corporation of New Jersey

Application May 16, 1940, Serial No. 92,411

Term of patent 14 years

To all whom it may concern:

Be it known that I, Lawrence E. Blazey, a citizen of the United States and residing in the town of Cleveland, county of Cuyahoga and State of Ohio, have invented a new, original, and ornamental Design for a Drafting Machine Elbow, of which the following is a specification, reference being had to the accompanying drawing, forming a part thereof.

Figure 1 is a perspective view of a drafting

machine elbow shown my new design with the arms at a slight angle to each other.

Figure 2 is a view in side elevation showing the drafting machine elbow with the arms in closed position.

I claim:

The ornamental design for a drafting machine elbow, as shown.

LAWRENCE E. BLAZEY.
